RADIO ALARM SYSTEM

William L. Foss, Washington, D. C., assignor to
Howton Radio Alarm Company, Seattle, Wash.

Application February 21, 1938, Serial No. 191,787

5 Claims. (Cl. 177—314)

It is the object of this invention to provide an alarm system, and more particularly to provide an improvement upon the radio alarm system shown in the copending application of James O. Howton, Serial No. 184,713, filed January 12, 1938.

In the present invention an interrupter device is provided, in addition to voice message reproducing means, to impress a code message on the carrier frequency in order that a suitable code message may be broadcast which will be intelligible even though an interfering voice broadcast, from another source, is occurring.

A preferred embodiment of the invention is diagrammatically shown in Figure 1 of the drawing. Figures 2 and 3 show a time control device, appearing also in Figure 1, in other positions assumed by it during its cycle.

The transmitter and control system here shown are essentially the same as that disclosed in the aforementioned Howton application. Several changes have been made in the wiring hook-up in order to connect the code signalling means into the transmitter circuit.

The transmitter disclosed in the Howton application is designed to broadcast on police and fire wave lengths. The protective system is so arranged that, when a burglar attempts to enter the building or when a fire is detected, an appropriate alarm message will be sent out to the authorities. The system embodies a relay control mechanism that selectively actuates a voice alarm reproducing device to cause the desired message to be played into the transmitter and at the same time renders the transmitter operative.

The present improved alarm system in addition to performing all of the above also sends a code message. It has been found in practice that when the relatively low powered transmitter unit in the protected premises is broadcasting and at the same time the central police radio transmitter is broadcasting, the more powerful police station will interfere with the voice message being sent out by the smaller set. This difficulty has been overcome by providing a code signal in addition to the voice message. With this means it is possible to broadcast an intelligible signal over a wide area, for though interference will still take place, the code message will over-ride and will be discernible over the interfering voice messages of the central police broadcasting station.

The transmitter has a piezo-crystal 10 to control the radio frequency. The controlled radio

frequency is imposed upon the grid of a tube 11, to the plate circuit of which is connected an inductance 12. The inductance has a variable condenser 13 connected across its terminals and a test jack 14 connected in line with a choke coil 15 which is in series between one terminal of the inductance and the positive terminal of a motor generator set 16. The test jack is provided in order that a meter may be temporarily connected into the circuit for tuning purposes.

In order to amplify the output of this first circuit, the output of the inductance is connected to the grid of a tube 17 through a capacitance 18. The plate of tube 17 is connected to an inductance 19 which has a variable condenser 20 across its terminals. The motor generator supplies suitable excitation to the plate of tube 17 through the series circuit containing choke 15, the secondary of a modulation transformer 21, and a test jack 22. Jack 22 provides a connecting means for a meter while tuning this stage of amplification. A code signalling device is connected in series with the cathode of tube 17, the operation of which will appear below.

Modulation of the radio frequency is accomplished by impressing the voice frequency upon the grid of a tube 23, the plate circuit of which is connected to the grid of a tube 24 in the next stage of amplification. The plate of tube 24 is connected to the primary of a transformer 25 the secondary of which is connected through a push pull circuit 26 and 27 to the primary of modulation transformer 21. The secondary of this modulation transformer is connected, as above described, into the plate of tube 17 and in this manner the voice frequency is superimposed upon the carrier frequency.

The modulated radio frequency currents thus created in the primary coil 19 of a radio frequency transformer 30 induce a current flow in its secondary which is in the antenna circuit. This antenna circuit is grounded through condenser 31 and the desired signal is thus broadcasted on the fire and police frequency to the fire and police authorities.

The above described circuit is designed to be compactly mounted within a suitable tamper-proof casing and all the necessary leads are brought to a central point where they are connected to a socket element 32a of the multiple point plug connector 32. The controlling means, responsive to the burglar and fire alarm circuits of the building, is adapted to be connected by the other element 32 of this plug connector to

the radio transmitting set to cause its operation when need be.

The controlling means for causing the operation of the transmitter, the code signalling device, and the voice alarm message reproducing means, is a system of relays connected between the fire and burglar alarm circuits and the radio transmitter. An electrical pickup impresses a recorded voice alarm message on the audio stage of the transmitter, the particular voice message which is broadcast depending upon which alarm circuit is disturbed. If both circuits are disturbed the two messages will be broadcast in alternating relation as will appear more fully below.

The fire alarm circuit through the building is normally open and the burglar alarm circuit normally closed, as shown in Figure 1. When the building is closed for the period to be protected the apparatus is set and through the circuit described below suitable relays are actuated to cause the operation of the alarm message reproducing means and the transmitter.

A support bar provides a row of suitable contact points or terminals A to J and the controlling circuit is hooked up through these points in the following manner:

A battery 35 is connected with its positive terminal to points F, H, and J and with its negative terminal to point E, the negative side of the burglar and fire alarms being connected to point E also. From point J a lead is provided that normally supplies current through contact 34 to relay 33, to point I which forms the positive or current supply terminal for the normally closed burglar alarm circuit. The point H is connected through normally deenergized relay 52 to point G.

The fire alarm circuit is connected across points E and G, this circuit normally being open, a potential is established across its terminals, such that a current will flow when the circuit is closed. Point F is connected to the normally open contacts 36, 40 and 53. Whenever either one of contacts 36 or 53 is made the circuit continues through relay 38, plug element 60 of a two contact connector. The corresponding socket element 60a of the connector continues the circuit through stop contact 39, back to the plug 60, and then to the point E. If the contact 40 is made the circuit continues through contact 41 to point C. The contact C is connected to the motor of the motor generator set 16, which motor is grounded to point D, which is connected to point E. Connected in parallel between points C and D are the motor 45 of the sound reproducing means and a supply for the filaments of the tubes of the transmitter which supply is connected to contacts 46 and 47 of plug element 32. The parallel circuit including the motor 45 has a switch 61, connected in series with the motor, that may be manually operated or that may be actuated by the voice alarm message reproducer to stop this voice alarm mechanism. Connected across points 46 and 47 of socket element 32a is a circuit through the motors 68 and 69 of the code signalling means.

The positive side of the generator of the motor generator set is connected to point A, the negative side to point B. Point A is connected to contact 43 of plug 32. Point B is connected to contact 44 and also forms a ground for the pickup arms 58 and 51. The pickup 58 is connected into circuit through the transmitter by contact 37 of relay 33, one side of the contact 37 being connected to contact 48 of plug 32. Pickup 51 is 75

connected to contact 54 of relay 52, contact 54 being connected in parallel with contact 37.

The code signalling means is connected with the transmitter circuit in a series circuit including tube 17 in the second stage of the radio frequency circuit. In the preferred form the code signalling means comprises a wheel 62 having a suitable code provided on its periphery. A contact arm 64 is adapted to engage the periphery of the wheel and its rotation makes and breaks the circuit through the contact arm in accordance with the code. The contact arm being in series with the cathode of tube 17, when the wheel is rotated the cathode circuit is alternately made and broken in a sequence such that the code is impressed upon the carrier frequency. It is obvious, of course, that the code message provided on the periphery of the rotating wheel is such as to apprise the authorities of a disturbance of one of the protective systems about the premises.

The above described circuits being established, the apparatus operates in the following manner:

When neither the fire nor burglar alarm circuits are disturbed the relay 33 remains energized by holding contact 34 closed establishing an energizing or holding circuit through battery 35. Relays 38 and 52 remain deenergized. This condition will prevail until the burglar alarm circuit in series with the battery and relay 33, is broken or the fire alarm circuit is made.

When the burglar alarm circuit is broken, it being in series with the battery and the relay 33, the current supply to the relay is stopped. Consequently the relay is deenergized and contact 34 is broken. While at the same instant contacts 36 and 37 are made. The breaking of contact 34 deenergizes relay 33 and to again become operative it must be manually reset. When contact 36 is made current is supplied from the positive terminal of the battery, to a circuit containing the relay 38, connector 60 and the contact 39, back to the negative of the battery. The energization of relay 38 makes contacts 40 and 41. The contact 40 being connected to the positive side of the battery, a current supply circuit is established through contact 41 to the motor of the motor generator set 16, which is grounded to the battery and the generator is operated to supply a suitable current (400 volts) to the radio transmitter through contact points 43 and 44 of plug member 32. Being connected in parallel with the motor circuit of the motor generator 16, the small motor 45 arranged to drive a turntable and the stop switch 61 connected in series therewith and the current supply through contacts 46 and 47 of plug 32 to the filaments of the radio transmitter tubes, these elements of the system are rendered operative by the closing of contacts 40 and 41. The energization of contacts 46 and 47 of socket element 32a causes the operation of the motors 68 and 69 of the code signalling means.

The code signalling device is designed to operate for a short period before the voice alarm message is permitted to be sent. Then the code message is blanked out for an interval and the voice alarm message is rendered intelligible throughout the area where no interference takes place. After the voice alarm message has been broadcast for a sufficient period, the code signalling device is again connected into the circuit so that the code message is impressed upon the carrier wave and sends the code message into such areas in which the voice alarm may have been interfered with.

To perform the above sequence of operations the cam element 65 is driven by the motor 68, and the code wheel 62 is driven by motor 69. These motors connected in parallel with the filament supply are energized as above explained and through suitable gear trains drive the cam and code wheels respectively. At the beginning of operations the cam wheel is in the position shown in Figure 1. Surface 70 does not engage contact 66 and the code message is impressed upon the carrier frequency as above described. When the cam has rotated to the position shown in Figure 2 surface 70 engages contact 66 short circuiting the code wheel and rendering the cathode continuously energized while the contact continues in engagement with the surface so that the voice alarm may be broadcast. As the cam continues its rotation and surface 70 is disengaged from contact 66, the code wheel again functions to send the code signal. The code is broadcast until the cam rotates to the position shown in Figure 3 where the arm 67 of the cam breaks the contact 39. As previously described the breaking of this contact deenergizes relay 38 so that the functioning of the transmitter is stopped.

A record, as disclosed in the copending application of William L. Foss, Serial No. 189,013, filed February 5, 1938, having two separate sound tracks is in position on the turntable and each track cooperates with a suitable electrical pickup. The two tracks are provided on one record so that from one track a message that the building is being broken into may be reproduced and from the other a message may be reproduced to the effect that a fire has been detected. The recordings on the different tracks are so related that in the case where both burglar and fire messages are required, first the burglar message will be given, then the fire message, the alarm messages will alternate in this manner, until the sound reproducer is stopped by the actuation of stop switch or by deenergization of relay 38.

Electrical pickup heads 50 and 51, here assumed to be of magnetic or static type, are mounted on the usual swingable arms so as to be able to follow the burglar and fire message tracks respectively. As above stated the deenergization of relay 33 causes contacts 36 and 37 to be made. The circuits established by contact 36 prepare the radio transmitter for operation. The making of contact 37 connects the burglar message pickup 50 into a circuit through the plug 32 to the grid of tube 23 of the audio frequency stage. The transmitter already being in operation the appropriate message reproduced through pickup 50 will be broadcast to the police authorities.

Referring to the condition of the alarm system when it has been properly set for guarding the building it will be remembered that the relay 33 is energized holding contacts 36 and 37 broken and making contact 34. In this circumstance when the fire alarm circuit is made, i. e. when a thermostat in the circuit is heated to such a temperature indicative of fire that it closes the circuit, a current is caused to flow in relay 52 such that it is energized, making contacts 53 and 54 which under normal conditions are always open. Relay 33 is still energized and maintains contact 34 closed and 36 and 37 open. Pickup 50 is withheld from operation while the fire message is sent because contact 37 is held open. Making contact 53 supplies current to the circuit containing relay 38 which, as above set forth,

starts the transmitter, code sending device, and turntable. The making of contact 54 establishes a circuit through the fire message pickup 51 and the grid of tube 23 of the audio-frequency stage of the transmitter. In this manner the code and voice alarm messages are broadcast calling attention to a fire within the protected area.

In the event that the burglar and fire alarm circuits should both be disturbed the relay 33 is deenergized and relays 38 and 52 are energized. The deenergization of relay 33 energizes relay 38 to set the transmitter and code device in operation and establishes a circuit through pickup 50. The energization of relay 52 establishes a circuit 15 through pickup 51. The transmitting set under these circumstances having both pickups and the code device in circuit with it, broadcasts both voice and code alarm messages. The record from which the voice alarm messages are being reproduced having the two nonconflicting series of tracks as above explained, the alarm messages do not interfere with one another when the voice alarm is being broadcast.

If the transmitter should accidentally be set 25 in operation, in order to prevent false alarms being sent out a manual control of the contact 39 is provided. It is possible by operating this contact to break the current supply through the relay 38. When this happens contacts 40 and 41 are released and break contact, the current supply to the motor of motor generator 16 is stopped, and the transmitter is thrown out of operation. It is, of course, obvious that the set and the contact would be situated in some concealed position 35 to render it inaccessible to unauthorized persons.

Whenever the protective system has been called into action it will continue to broadcast for a predetermined period of time. This period is controlled by the arm 67 of the cam and contact 39, i. e. the set will broadcast until the arm actuates the contact. This, as above explained, stops the motor generator set and renders the transmitter inoperative. In order to again condition the set for operation it is necessary to 45 reset the relay control system. This is done by closing the burglar alarm circuit and/or opening the fire circuit making it possible to reenergize relay 33 by making contact 34. The cam 65 is reset and also pickup arms 50 and 51. The contact 39 is made and the system is in operative 50 position to protect the building.

The relay control system like the transmitter is compactly designed to fit within a tamper-proof casing and has all of its leads that cooperate with the transmitter brought out to the plug element 32 of the multiple connector and plug element 60 of the two point connector. The other leads of the control system, which are connected to the burglar and fire alarm circuits, the battery, and the motor generator set are brought out to the terminal support bar for convenience in hooking up the protective system.

From the foregoing description it is clear that any building to be protected by this apparatus is first wired with properly designed fire and burglar alarm circuits. These circuits are connected to the terminal support bar of the concealed control unit and the control unit is plugged into the transmitter unit. As soon as a 65 battery and motor generator set have been connected up, the system is in condition for operation. By this means a thoroughly reliable, compact, and simple broadcasting station is situated in the building to be protected and the unit is effective to automatically call the police and/or

fire department upon any tampering with the building.

It is obvious, of course, that the normally closed burglar alarm and the normally open fire alarm circuits could be interchanged so that a closing of the burglar circuit and an opening of the fire circuit would initiate operations. However the preferred hookup is as above described. Other modifications will appear to those skilled in the art, all of which are included within the scope of the appended claims.

I claim:

1. A radio alarm system comprising a transmitter including a plurality of tubes and alarm message producing means in connection with said transmitter, said means including code signalling means and a motor for said last named means, means for blanking out said code signalling means and a motor to drive said blanking means, said motors being connected in parallel with each other and in parallel with the filament supply circuit for said tubes, means for controlling the operation of the last named means, said alarm message producing means including also voice message producing means, and means for operatively connecting said voice message producer with the transmitter while the code signalling means is blanked out, said alarm system being adapted to transmit a warning of a disturbance on a protected premise, said voice message producing means being effective when actuated to cause a warning signal to be broadcast and said code signalling means being effective when actuated to send an intelligible signal into zones of possible interference.

2. A radio alarm system comprising a transmitter and alarm message producing means in connection with said transmitter, said means including code signalling means, means for blanking out said code signalling means including a plurality of successively operated circuit controls, one of said contacts making a short circuit around said code signalling means, another of said contacts being operative to stop said transmitter, means for controlling the operation of said blanking out means, said alarm message producing means including also voice message producing means, and means for operatively connecting said voice message producer with the transmitter while the code signalling means is blanked out, said alarm system being adapted to transmit a warning of a disturbance on a protected premise, said voice message producing means being effective when actuated to cause a warning signal to be broadcast and said code signalling means being effective when actuated to send an intelligible signal into zones of possible interference.

3. An alarm system including a radio transmitter having an audio frequency stage and a radio frequency stage, said last named stage including a cathode tube, a plurality of different

voice alarm messages, means to cause said different messages to be selectively impressed upon said audio frequency stage, a code message adapted to be impressed upon the cathode of said tube, means to initiate said voice alarm and said code alarm to cause a broadcast thereof, and means to cause said code message to override said voice alarm at spaced time intervals whereby the alarm signal is transmitted to distant points irrespective of other voice messages which may be being broadcast on the same wave band as said radio transmitter.

4. An alarm system including a radio transmitter having an audio frequency stage and a radio frequency stage, a plurality of different voice alarm messages, means to cause said different messages to be selectively impressed upon said audio frequency stage, a code message adapted to be impressed upon said radio frequency stage, means to initiate said voice alarm and said code alarm to cause a broadcast thereof, said means comprising a plurality of protective circuits wired around the premises, a relay system between said circuits and said transmitter controlled by said circuits, said relay system being effective to cause an energization of said transmitter and selectively impress the voice alarm message to be broadcast on the carrier frequency, and means to cause said code message to override said voice alarm at spaced time intervals whereby the alarm signal is transmitted to distant points irrespective of other voice messages which may be being broadcast on the same wave band as said radio transmitter.

5. An alarm system including a radio transmitter having an audio frequency stage and a radio frequency stage, said last named stage including a cathode tube, a plurality of different voice alarm messages, means to cause said different messages to be selectively impressed upon said audio frequency stage, a code message adapted to be impressed upon the cathode of said tube, means to initiate said voice alarm and said code alarm to cause a broadcast thereof, and means to cause said code message to override said voice alarm at spaced time intervals, said last named means including a code producing device and a time driven circuit maker and breaker, said circuit maker and breaker comprising a contact wheel and switch actuating finger serving to sequentially connect said code producing means into series with said cathode tube and then short circuit and code producing means and then again connect said code producing means in series with said cathode and then said finger serving to break the energizing circuit of said transmitter, whereby the alarm signal is transmitted to distant points irrespective of other voice messages which may be being broadcast on the same wave band as said radio transmitter.

WILLIAM L. FOSS.
